UNITED STATES PATENT OFFICE.

JOHN PRIMROSE, OF NEW YORK, N. Y.

STEAM-SUPERHEATING APPARATUS FOR LOCOMOTIVES

1,037,313.

Specification of Letters Patent.

Patented Sept. 3, 1912.

Application filed May 27, 1907. Serial No. 375,784.

To all whom it may concern:

Be it known that I, JOHN PRIMROSE, a subject of the King of Great Britain, residing at New York, in the county of Kings and State of New York, have invented certain new and useful Improvements in Steam-Superheating Apparatus for Locomotives, of which the following is a specification, reference being had to the drawing accompanying and forming part of the same.

My invention relates to steam superheaters and has for its chief object to provide a simple and efficient superheating apparatus for use with boilers of the locomotive type.

In carrying out the invention in the preferred manner the superheater is inclosed in a suitable chamber or casing which is arranged transversely across the boiler, somewhat nearer the fire-box than the smoke-box end of the boiler. The superheater chamber is preferably a box of rectangular cross section, with its ends opening through the sides of the boiler; or the chamber or box may be formed of two spaced tube-sheets, reaching from the bottom of the boiler to a suitable height, where it is provided with a cover or roof. At each end of the box is a lined door, so that each end of the superheater is readily accessible for cleaning, inspection, repairs, etc. The boiler tubes or flues which would otherwise pass through the space occupied by the superheater chamber are made in two lengths, those leading from the fire box discharging the furnace gases into the superheating chamber, while those forward of the chamber convey the gases therefrom to the smoke-box. The superheater, which is disposed in an advantageous manner in the chamber, is thus subjected to hot gases at a higher temperature than they would possess after passing through the entire length of the tubes, and a higher superheat can therefore be obtained than is possible with the superheater located in the smoke box.

A very effective embodiment of the invention is illustrated in the annexed drawings, to which reference may now be made.

In the drawings, Figure 1 is a side elevation of a locomotive boiler, with the end of the superheating chamber in section to show the superheater in place therein. Fig. 2 is a top plan view of the portion of the boiler in which the superheating chamber is lo-

cated, showing the manner of connecting the superheater with the steam space of the boiler. Fig. 3 is a detail view on a larger scale, in longitudinal section, taken on line III of Fig. 2. Fig. 4 is a detail view on a larger scale, in transverse section taken on line IV-IV of Fig. 2. Fig. 5 is a sectional view, on the same plane as Fig. 3, of a modification, showing another type of superheating chamber.

The preferred form of superheating chamber is shown in Figs. 1 to 4, and consists of a rectangular box 1, extending transversely across the boiler, 2, at a point somewhat nearer the fire-box, 3, than the smoke-box, 4. The ends of the chamber project through the sides of the boiler and are provided with removable closures 5, 6, to afford ready access to the interior. The chamber is secured in position in any suitable manner so as to make tight joints with the boiler shell, and the top and bottom of the chamber may be supported in the same way as the flat surfaces of the combustion chambers common in marine-boiler practice. By reason of its rectangular shape the chamber forms the best possible support for the portions of the boiler otherwise left unsupported when the openings in the sides are made. All of the strains produced by steam pressure against the boiler shell are taken by members of the box in tension; and since, as will be seen, there is no tendency for the box to get out of shape there is practically no danger of leaks. The ends of the tubes, 6^a, are rolled into the front and rear walls of the chamber, as shown in Fig. 3. The furnace gases therefore flow through the chamber in their passage to the smoke-box. The superheater itself is preferably composed of two sections, extending from end to end of the chamber, across the boiler, each composed of vertical inlet and outlet headers 7 and 8 respectively, and intermediate horizontal tubes 9. The inlet headers 7 extend through the top of the chamber, outside of the boiler, and are connected by bends 10 to the supply pipe 11-12, inside the boiler and receiving steam from the dome 13. The outlet headers 8 extend through the bottom of the chamber and are connected by pipes 14, 15, to the respective engines at the forward end of the boiler. The steam from the boiler therefore divides at the pipe 11, and flowing once through the superheater tubes, in parallel, passes out of the superheater at

the ends of the chamber and is delivered to the engines. The throttle, 11, is in the pipe 12. Any approved type of superheating tubes may be employed, but I have found that the well known "Foster type" of tube is the best construction for the apparatus described, and I have therefore shown the superheater provided with such tubes. They consist of a foundation tube 16, providing the necessary strength for the element, and a casing composed of cast-metal tapered rings 17, shrunk in place on the foundation tube. The rings increase the heating surface of the tubes, and at the same time the large mass of metal thus introduced absorbs a considerable amount of heat, thus preventing overheating when starting up or when no steam is passing through, so that automatic devices for protecting the superheater at such times are unnecessary. Also, the heat held by the casing prevents rapid cooling of the superheater when steam is not going through the tubes and the fire is checked, so that when steam is again sent through the superheater the steam will leave the superheater at a higher temperature than would be the case if the cast metal casing were not used.

In the modified construction shown in Fig. 5 the front and rear walls of the chamber are carried down to the bottom of the boiler, like tube sheets, as 18, 19, and to protect the boiler shell the bottom of the chamber is lined with fire-brick, as shown at 20. At a convenient point is an aperture provided with a closure 21, to permit easy removal of cinders, soot, etc., from the chamber. This form of chamber lacks the bottom plate of the other type of chamber, but its place may be supplied by transverse bars, not shown, below the superheater. In both forms of superheating chamber the superheater is spaced from the front and rear walls sufficiently to permit the insertion of a blower tube having its nozzle bent at right angles, for the purpose of blowing soot out of the boiler tubes.

Because of the high degree of superheat ordinarily desirable in locomotives and because of the limited size of superheater that can be used, due to the restricted space available therefor, it is necessary to have the gases come in contact with the superheater at as high a temperature as the superheater elements will stand. In accordance with these requirements the superheating chamber described herein may be located at any suitable point between the fire-box and the smoke-box; and if the tubes are of the Foster type, described above, the superheater may be placed much nearer the fire-box, with correspondingly higher superheat, than if tubes of the ordinary kind are used. Numerous other advantages flow from the invention described herein. For example,

the boiler tubes and the superheater can readily be cleaned of soot, etc., by means of a steam or air jet operated through the ends of the chamber. The superheater is easy of access and can be readily removed. If it is desired to operate the boiler without the superheater it is only necessary to remove the latter and substitute short filling-in pipes in the steam line. Although the boiler heating surface is reduced by the omission of portions of the fire-tubes, this does not mean that evaporation will be reduced in the same proportion, for the reason that the superheater will absorb less heat from the gases than would the omitted portions of the fire tubes. Hence the temperature of the gases entering the tubes at the smoke-box side of the chamber will be higher than it would be at the same point if the tubes were continuous; consequently there will be a greater difference of temperature between the gases, in the outlet fire-tubes, and the water surrounding the latter; and more water will therefore be evaporated. The present satisfactory arrangement of exhaust nozzles, screens, etc., in the front end of the locomotive is not disturbed as would be the case with a superheater located in the smoke-box. Other advantages will be apparent to the skilled engineer, but these thus briefly referred to are sufficient to show the marked utility of the invention and that it avoids or obviates most, if not all, of the objections heretofore urged against the use of superheaters in locomotives.

It is of course understood that the apparatus herein specifically illustrated and described is merely the preferred form of the invention and may be modified without departure from the spirit of the invention as defined by the appended claims.

What I claim is:

1. The combination with a boiler having fire-tubes; of a superheating chamber extending across a plurality of fire-tubes and connected thereto; a superheater in the chamber, spaced from the open ends of the said connected fire-tubes to permit the introduction of a nozzle for projecting a blast into the tubes to clean the same; the superheating chamber having opposite ends projecting through openings in the side walls of the boiler, a heating tube in the chamber, and headers secured to the projecting ends and communicating with said tube, as set forth.

2. The combination with a boiler having fire-tubes; of a superheating chamber extending transversely through the boiler, connected with a plurality of fire-tubes and having its ends extending outside the boiler; and a superheater in the chamber, comprising inlet and outlet headers at the ends of the chamber exterior to the boiler shell, and

superheating tubes connecting the same; as set forth.

3. The combination with a boiler having a fire-box and fire-tubes leading therefrom, and boiler having oppositely disposed openings in its side walls, of a superheating element extending transversely of the boiler and connected with said fire-tubes, the ends of the chamber projecting through the openings in the boiler, headers located in the ends of said chamber, steam pipes connecting the headers, and closures for said openings.

4. In a steam boiler, the combination with discontinuous fire-tubes, of a superheating chamber located between the sections of said tubes, the superheating chamber comprising a substantially rectangular body portion projecting at its opposite ends through opposite sides of the boiler shell.

5. In a steam boiler, the combination with discontinuous fire-tubes, of a superheating chamber located between the sections of said tubes the superheating chamber comprising a substantially rectangular body portion projecting at its opposite ends through opposite sides of the boiler shell, and superheating tubes within the chamber.

6. In a steam boiler, the combination with discontinuous fire-tubes, of a superheating chamber projecting across the path of the discontinuous fire-tubes and connected thereto to establish communication between the discontinuous sections thereof, and said superheating chamber projecting through openings in opposite sides of the boiler shell.

7. In a steam boiler, the combination with discontinuous fire-tubes, of a superheating chamber located between the sections of said tubes, the superheating chamber comprising a substantially rectangular body portion projecting at its opposite ends through opposite sides of the boiler shell, and superheating tubes within the chamber, and removable closures at the projecting ends of said chambers.

8. The combination with a boiler of the locomotive type, having a fire-box and a smoke-box connected by fire-tubes, of a superheating chamber between the fire-box and the smoke-box arranged in the path of and extending transversely across a plurality of fire-tubes and connected thereto, said chamber being of less height than the vertical diameter of the boiler and supported above the bottom thereof, whereby to leave above and below the chamber free communication for steam and water in the portions of the boiler in front and rear of the chamber, and a superheater mounted in the chamber and connected with the steam space of the boiler, and means for conveying the superheated steam from the superheater to the engine.

9. The combination with a boiler of the locomotive type, having a fire-box and fire-tubes leading therefrom, of a box-like superheating chamber extending through the side walls of the boiler in front of the fire-box and across a plurality of the fire-tubes, the bottom of said chamber being spaced above the bottom of the boiler and the top of the chamber being spaced below the top of the boiler whereby to provide free communication between the front and rear portions of the boiler, a superheater mounted in said chamber and connected with the steam space of the boiler, and removable closures for the projecting ends of the superheating chamber.

10. The combination with a boiler of the locomotive type, having a fire-box and a smoke-box at opposite ends, and fire-tubes connecting the two, of a superheating chamber extending transversely through the boiler and secured to the side walls of the boiler, a plurality of the fire-tubes being connected to the front and rear walls of the chamber to deliver furnace gases to the chamber and convey such gases from the chamber to the smoke-box, the bottom of the chamber being spaced above the bottom of the boiler and the top of the chamber being spaced below the top of the boiler, a pair of superheaters mounted in the chamber, means for conveying steam from the boiler to the superheaters, and independent means for conveying superheated steam from the superheaters to the respective engines.

11. The combination with a boiler of the locomotive type, having a fire-box and a smoke-box and fire-tubes connecting the two, of a superheating chamber in the form of a rectangular box, extending transversely through the side walls of the boiler and across a plurality of the fire-tubes, to which the front and rear walls of the chamber are connected, the top and bottom of the chamber being spaced from the top and bottom respectively of the boiler, whereby to provide free communication above and below the chamber between the front and rear portions of the boiler, vertical inlet headers in the ends of the superheating chamber and outside of the boiler, outlet headers alongside of the inlet headers, superheating tubes connecting each inlet header to the outlet header on the opposite side of the chamber, means for delivering steam from the boiler to the inlet headers, and means for conveying steam from the outlet headers to the respective engines.
